UNITED STATES PATENT OFFICE.

JOHN SWEENEY, OF NEW HAVEN, CONNECTICUT, ASSIGNOR OF ONE-THIRD
OF HIS RIGHT TO JAMES T. LEIGHTON, OF SAME PLACE.

CAR-DOOR.

SPECIFICATION forming part of Letters Patent No. 232,153, dated September 14, 1880.

Application filed June 24, 1880. (No model.)

To all whom it may concern:

Be it known that I, JOHN SWEENEY, a citizen of the United States, residing at New Haven, in the county of New Haven and State of Connecticut, have invented certain new and useful Improvements in Car-Doors; and I do hereby declare the following to be a full, clear, and exact description of the invention, such as will enable others skilled in the art to 5 which it appertains to make and use the same, reference being had to the accompanying drawings, and to letters or figures of reference marked thereon, which form a part of this specification.

15 This invention relates to doors for box-cars; and it consists in the peculiar construction and combination of parts hereinafter set forth and claimed.

The same letters of reference indicate the 20 same parts in the different figures of the drawings.

Figure 1 represents an exterior elevation of my improved door, and Fig. 2 an elevation of the same taken from the inner side.

25 The door as a whole runs on rollers on the outside of the car, so that it may be shifted horizontally to open or close the doorway in the usual manner.

A designates the wooden body of said door, 30 consisting of strips *a*; and B, a metallic frame which incloses it. This frame consists of side walls, B' B', and cross-pieces B². The sides B' are provided with exterior flanges, *b*, one to each wall, running the entire height of the 35 vertical edge of the door and overlapping and bracing the wooden body A. The horizontal cross-pieces B² are provided with feet *b'*, whereby they are secured to the said side walls, B'. These cross-pieces are made of angle-iron, and the vertical portion of each cross-piece is constructed with a series of slots or horizontally-elongated holes, *b²*. Space is left for the wooden body A between the cross-pieces B² and the exterior flanges, *b*, and the said 40 body A is secured to the frame by screws C, or equivalent fastening devices, which pass through said slots or holes *b²*.

The wooden body A preferably consists, as

shown, of a series of strips of sheathing arranged edge to edge; and to provide for the 50 unequal expansion of the several strips the oblong slots *b²* allow them to contract or expand, according to the dryness or moisture of the air without straining on the points of attachment.

55 The outer flanges, *b*, protect the wooden part of the door from injury at the points where it is most exposed. They may be extended across the top and bottom of it also, if desired.

60 The door cannot warp, as the cross-pieces B² will not bend. Hence it necessarily always retains its proper shape and is in condition for service.

65 The angular construction of all parts of the frame B secures the greatest possible amount of strength consistent with the requisite degree of lightness.

Having thus fully described my invention, what I claim as new, and desire to secure by 70 Letters Patent, is—

1. In combination with the wooden body A, the metal frame B, consisting of side pieces, B', having exterior flanges, *b*, and cross-pieces, B², having feet *b'*, the said body A being secured to said cross-pieces.

2. In combination with frame B, having cross-pieces B², which are provided with slots or oblong holes *b²*, the fastening-screws C, passing through said slots, and the strips *a*, forming the wooden body A, and held by said screws in said frame in such manner as to allow contraction or expansion, as set forth.

3. A car-door consisting of a metallic frame and a wooden body.

4. A car-door consisting of a metallic frame and a wooden body, said parts being constructed in such manner as to allow the expansion and contraction of the wooden portion of the door independently of the frame.

In testimony whereof I affix my signature in presence of two witnesses.

JOHN SWEENEY.
